UNITED STATES PATENT OFFICE

CHARLES W. ANDREWS, OF DULUTH, MINNESOTA, ASSIGNOR, BY DIRECT AND MESNE ASSIGNMENTS, TO H. A. BRASSET & COMPANY, OF CHICAGO, ILLINOIS, A CORPORATION OF ILLINOIS

METHOD FOR MAKING PRODUCER GAS

Application filed October 31, 1925. Serial No. 65,940.

This invention relates to a new and improved method for making producer gas and more particularly, to such a method in which thermal efficiency is increased by 5 operation under the counter-current principle of heat transfer.

It is well known in the art that the amount of steam used in gas producers is largely governed by the character of the ash.

10 Should it clinker easily, more steam is required to prevent clinkers as up to the present time there is no mechanical ash removing device which will adequately handle large pieces of hard clinker. Although the 15 slagging type of gas producer has been developed to solve this problem and also makes possible a deep fuel bed, nevertheless no commercial installations are known to be in use in this country owing to trouble in making liquid slag and removing it.

It is recognized that carbon monoxide is a better gas than hydrogen for many heating operations on account of its greater specific 20 gravity and also on account of the increased 25 radiation from the burning gas. It is also recognized that the undecomposed steam passing through the producer is detrimental as it not only requires heat to make it, but it also carries out of the fire bed its own 30 sensible heat. This is especially objectionable in high temperature operation as the flame temperature is materially lowered. The amount of blast furnace gas or other carbon dioxide containing gases it is pos-

35 sible to use in place of steam, depends upon the fire temperature which must be sufficiently high, not only to effect the desired decomposition of carbon dioxide, and also, the decomposition of the small quantity of 40 water vapor which is usually found with the gases, but also to supply the amount of sensible heat the gases carry out of the fire bed of a producer. This is a considerable item as gas producers ordinarily run at a 45 top temperature around 1300 to 1400° F. It is evident that if the counter-current principle of heat transfer could be used a material saving could be obtained. However, the result of such a procedure would 50 be the formation of large clinker masses,

which up to this time has made such a method of operation impracticable.

The applicant has recognized the above and in co-pending applications has sought to better these results by various means. The 55 application of the applicant, Serial No. 1,157, filed January 8, 1925, issued April 16, 1929 as Patent No. 1,709,107, discloses a method of breaking up such clinkers and the joint application of Chapman and the applicant, Serial No. 737,238 filed September 12, 1924, issued April 16, 1929, as Patent No. 1,709,334, shows the necessary mechanical 60 means to accomplish the purpose. Inasmuch as these inventions have been perfected, it is now possible to operate a gas producer for thermal efficiency without being handicapped by the formation of the large 65 clinkers. Relatively deep fire beds and also much higher temperatures can be used, both 70 resulting in a largely increased production per unit of capacity and also making a better gas, as practically all of the steam used will be decomposed and the percentage of 75 CO₂ reduced to a minimum. It is also now possible to operate such a producer so as to take advantage of the counter-current principle, referred to above. Air and steam or 80 blast furnace and other gases may be admitted from either top or bottom, either together or alternately, whatever way may be most desirable. Blast furnace or other gases may be substituted wholly or in part for 85 the steam now used.

Heat transfer from the outgoing to the incoming gases can be readily accomplished either by using the top and bottom sections of the deeper beds of fuel and ash as regenerators, this being made possible by the aforesaid inventions, or by constructing external regenerators or recuperators for the purposes. If a separate regenerator is used it provides means for producing the required steam, or acts as a standby source of steam supply should blast furnace or other gases be normally used, as the checkerbrick in the regenerators can be so constructed as to be readily used as a flash boiler.

It is an object of the present invention to 90 provide new and improved means for the 95 100

production of producer gas with great thermal efficiencies.

It is a further object to provide a method in which a gas is produced by flow reversals involving the transfer and conservation of heat by means of the counter-current principle.

It is an additional object to provide a method in which the heat of the gases finally leaving the apparatus is reduced to a minimum and which may be carried out in various manners by the joint or separate use of air, steam and metallurgical gases containing a considerable portion of carbon dioxide.

Other and further objects will appear as the description proceeds.

I have illustrated in the accompanying drawings a preferred form of apparatus adapted for carrying out my improved method, the apparatus being in itself no part of the present invention.

In the drawings, Figure 1 is a vertical section of the apparatus and

Figure 2 is a horizontal section taken on line 2—2 of Figure 1.

The apparatus comprises the gas producer 11 having the charging bell 12 and the fixed 16 grate 13. The bar or agitating beam 14 extends across the grate and has its ends secured to the ring 15 which rotates upon the balls 16. The lower portion of the ring is provided with the gear 17 which is driven 21 by means of pinion 18. Power is supplied to the pinion 18 in any desired manner. The bottom of the producer is entirely enclosed by the housing 19. The circular ash tray 20 is carried by the ring 15 and ashes are 26 scooped from the tray by means of the adjustable scoop 21. Ashes are moved through the door 22. Ashes falling through the grate 13 may be removed through the door 23. The bottom housing 19 is connected to the 31 passage 24 controlled by valve 25 and the passage 26 controlled by valve 27 leads from the passage 24.

This type of apparatus is shown more in detail in my co-pending application, Serial 50 No. 1,157 filed January 8, 1925 now issued as Patent 1,709,107 of April 16, 1929. The regenerator 28 which is provided with the heating flues 29 has its upper end connected by passage 30 with the upper end of the 55 gas producer 11. The passage 31 controlled by valve 32 leads into the lower end of the regenerator 28. The passage 33 controlled by valve 34 leads upwardly from the passage 31.

60 In carrying out my method by the use of this apparatus, the air, air and steam, or blast furnace or other gases such as spent or burnt or partially burnt gases from other furnaces or apparatus, and containing carbon dioxide and which are to be used are

introduced through the passage 24, the valve 25 being opened. These pass upwardly through the ash and clinker in the bottom of the producer, then through the fire zone and upwardly through the raw fuel in the upper portion of the producer in which a thick fuel bed may be carried. The oxygen in the gases unites with the carbon of the fuel to form carbon monoxide and this gas forms the basis of the gas desired. The heated gases, after giving up some of their heat to the fuel in the upper portion of the producer then pass through passage 30 to the regenerator 28 where they give up additional heat and are led off through passage 31, valve 34 being closed and valve 32 being opened, to the desired point of use or to gas holding apparatus, not shown. The gas run may be then reversed and the incoming gas or gases brought in through passage 31, and passed through the regenerator where they pick up heat, then passed down through the fuel and out through the clinker and ash where they give up much of their heat before being led off through the passage 24 to the point of use or to a gas holder.

It will be understood that the gases used and introduced into the producer may be widely varied. Steam and air may be introduced alternately or together. It should be noted, however, that this alternate introduction of steam and air will not be for the purpose of producing water gas according to the water gas cycle of operation. The gas to be made is producer gas containing nitrogen and with carbon monoxide as its major combustible component. The air may be introduced under low pressure as in producer practice and when the heat of the fire is raised to as high a point as is desired for the production of carbon monoxide, irrespective of the formation of large clinkers, the supply of air will be shut off and steam introduced to cool the fire, largely by its decomposition, to such a degree as may be desired for efficient operation. The air and steam may be introduced together if desired, in which case, they will be proportioned so as to maintain the desired fire temperatures for gas production without relation to clinker formation.

It will be understood that the main purpose for the introduction of steam in usual producer practice is not the production of blue water gas to mingle with the carbon monoxide formed by the imperfect combustion caused by the air introduced, but is the maintenance of proper working temperatures and the utilization of the excess heat of the combustion. A continuous air blast alone would produce a gas of low latent heat content leaving the producer at a high temperature with consequent loss of sensible heat and would further raise the temperature in the producer so high as to clog it

with molten slag. By the introduction of steam in proper proportions, the excess heat of the exothermic reaction of combustion is utilized in the endothermic reaction of dissociating the steam. The products of the latter reaction are combustible and thus much of the heat is utilized in making useful gas. Due to continuous operation in one direction, however, in ordinary producers 10 much sensible heat is lost as the gas leaves the producer at a relatively high temperature.

Metallurgical gases such as blast furnace or other gases which contain much carbon dioxide together with some carbon dioxide and water vapor, may be substituted for steam in my improved method of operation. These gases reduce the temperature in the producer and utilize the excess heat of combustion by the endothermic reaction of breaking down the CO_2 to CO as well as the reaction of breaking down the water of any water vapor content. Such gases thus function in substantially the same way as steam 20 insofar as the process broadly is concerned.

Where blast furnace or other metallurgical gases are used, which gases contain a large proportion of carbon dioxide, these gases may be alternately introduced from 30 above and below as has been described. The carbon dioxide of the gases will react upon the carbon of the fuel and will be largely broken down to carbon monoxide, thus very greatly raising the heat value of the gas.

By the use of apparatus of the general type shown and described, my method may be advantageously carried out. A minimum of heat is carried away from the apparatus, since by the application of the counter-current principle much of the heat is retained. In the downrun, this heat is retained in the clinker and ash below the fire zone and is picked up by the incoming gases upon the uprun. Upon the uprun, in the form of 40 construction shown, some of the heat is retained by the fuel above the fire zone in the producer and additional heat is retained in the regenerators shown.

Obviously, the apparatus is capable of 50 modification, such for example, as supplying an additional regenerator associated with passage 24 so that regeneration of the incoming air and gas may be had in both up and down runs. On the other hand, the regenerator shown may be dispensed with and by using deep fuel beds, the ash and clinker below the fire zone and the fuel above the fire zone may be the sole regenerating means. The revolving bar of the type shown serves 60 to drop the clinkers off of its vertical edge and to break them up into small masses which are readily discharged and removed. The method of operation which produces large clinker masses is, therefore, not objectionable when using this apparatus since 65

these masses are broken up and removed without difficulty in the normal operation of the apparatus.

When using blast furnace gases in the producer, these gases will be used as they come from the blast furnaces without being washed and their content of iron and other materials will be taken up by the fuel and ash in the producer as the gas is passed through. The iron will be present in the 70 clinker coming from the producer and this clinker may be charged back into the blast furnace and the iron recovered in this manner. No sintering will be necessary. This method, therefore, has the advantage of recovering the iron content of the blast gases 80 directly in a usable form and avoids the necessity for washing the gases. The gases are also enriched by largely breaking down their carbon dioxide content to carbon monoxide. 85

While one form of apparatus particularly adapted for carrying out my process has been shown in the accompanying drawings, it is to be understood that it may be carried 90 out by other apparatus and I contemplate such changes and modifications as come within the spirit and scope of the appended claims.

I claim:—

1. The method of making producer gas, which comprises admitting mixtures of air and gases containing a substantial quantity of carbon dioxide gases, said gases being capable of forming more combustible gases 100 through endothermic reactions in a highly heated deep fuel bed, said admissions being alternately from the top and bottom of a gas producer, the periods of alternation being so timed as to cause the sensible heat of the out-going gases to be largely transferred to the incoming gases, and continuously breaking up and removing mechanically the ashes and clinkers which 105 form.

2. The method of making producer gas, which comprises the successive admission of air and of combustible gases containing substantial quantities of carbon dioxide, said combustible gas being capable of forming more highly combustible gas through endothermic reactions in a highly heated deep fuel bed, said successive admissions of air and gas being alternately from the top and bottom of a producer, the periods of alternation being such as to cause the sensible heat of the out-going gases to be largely transferred to the in-coming gases, and continuously breaking up and removing mechanically the ashes and clinkers which 110 form. 115

3. The method of making producer gas, which comprises the successive admission of mixed air and combustible gases containing substantial quantities of carbon dioxide, 120 125

130

said combustible gas being capable of forming more highly combustible gas through endothermic reactions in a highly heated deep fuel bed; such said successive admissions of mixed air and gas being alternately from the top and bottom of a gas producer passing the outgoing generated producer gas into a regenerator in heat exchange with the incoming air and gas whereby the sensible heat of the producer gas is largely transferred to the incoming mixed air and gas, and continuously breaking up and removing mechanically by an agitating beam, the ashes and clinkers which form.

15 Signed at Chicago, Illinois, this 28th day of October, 1925.

CHARLES W. ANDREWS.
